UNITED STATES PATENT OFFICE.

MILTON CHASE, OF HAVERHILL, MASSACHUSETTS.

NAIL-BLANK PLATE.

SPECIFICATION forming part of Letters Patent No. 436,401, dated September 16, 1890.

Application filed November 11, 1889. Serial No. 329,836. (No model.)

To all whom it may concern:

Be it known that I, MILTON CHASE, a citizen of the United States, residing at Haverhill, in the county of Essex and State of Massachusetts, have invented certain new and useful Improvements in Nail-Blank Plates, of which the following, taken in connection with the accompanying drawing, is a specification.

My invention relates to certain improvements in nail-blank plates; and it consists in a plate of peculiar form, which when cut up into strips will produce spear-headed nails for blind-nailing in boots and shoes, the width of the plate representing the form and length of several nails, so that by one cut through the plate a corresponding number of spear-headed nails are produced.

Referring to the accompanying drawing, the figure represents a nail-blank plate for making nails with spear-heads embodying my invention.

The width of the plate is equal to the length of several nails, and the two surfaces are rolled to the form shown—that is, so as to form the bodies *d* of the nails, which at their upper ends are depressed to form notches *e*, and then again enlarged to form the spear-heads *f*. The portions *a*, that are intended to form the points, are not quite separated from the portions *b*, that are to form the heads of

the next adjacent nails, so that when passed through a shearing-machine a certain length of the plate (equal to the width of the nail required) is cut off, which strip can then be separated at the junction of the points *a* and heads *b*, (by a tumbler or other means,) and form a number of separate and independent spear-headed nails, although only one cut has been made from the plate. The nails when thus cut and separated appear as shown at *E*. 35 The main body *d* of the nail is intended to be driven into the heel of the boot and the spear-head *f* left projecting, and upon which the upper lift is forced and there held by the notch *e* under the spear-head. If desired, 40 45 the plate might be cut up into strips first and then into nails.

What I claim as my invention is—

A nail-blank plate the two end edges of which represent the form of spear-headed 50 nails, substantially as shown and described.

In testimony whereof I have signed my name to this specification, in the presence of two subscribing witnesses, on this 15th day of April, A. D. 1889.

MILTON CHASE.
